UNITED STATES PATENT OFFICE.

HARRY BARRETT WEBB, OF NEW WESTMINSTER, BRITISH COLUMBIA, CANADA.

SHINGLE-MACHINE SPUR-ROLL RATCHET.

Application filed October 4, 1923. Serial No. 666,652.

To all whom it may concern:

Be it known that I, HARRY BARRETT WEBB, a subject of the King of Great Britain, and a resident of the city of New Westminster, 5 in the Province of British Columbia, Canada, have invented certain new and useful Improvements in Shingle-Machine Spur-Roll Ratchets, of which the following is a specification.

My invention relates to improvements in ratchets for use in the operation of the spur rolls of shingle machines, although the invention may be employed with equal facility and advantage for other analogous purposes, 15 and the object of my invention is to provide a ratchet which while of light, compact, and simple construction is yet strong and efficient, possessing the maximum wearing surface within the limits of its convenient size 20 without detracting from its practicability, and in which a very fine adjustment of feed may be attained, reducing backlash to a minimum and eliminating undue slackness and wear. A further object is to devise an 25 efficient and practical internal ratchet, that is, one which is adapted to be completely enclosed so that it is protected from dust and can be run in an oil bath so that it is smooth in operation and is maintained in 30 perfect working order with the minimum of attention and repair.

I attain these objects by the construction illustrated in the accompanying drawings in which—

Fig. 1 is a side elevation of the ratchet.
Fig. 2 is an edge view.

Fig. 3 is a side elevation with one side of the cover removed.

Fig. 4 is a cross sectional view taken 40 through the line 4—4 of Fig. 3.

Fig. 5 is a slightly reduced cross sectional view of the pawl disc.

Fig. 6 is a view illustrating the ratchet mounted on a spur roll.

Fig. 7 is a view showing the ratchet and its associated bell crank and lever.

Similar figures of reference indicate similar parts throughout the several views.

The device consists of an annular plate 50 disc 1 having a central bore 2 extending through concentric bosses 3 and 4 on each side of the disc, the bore 2 being adapted to be fitted on and secured to the end of the spur roll shaft, as indicated in Figs. 6 and

55 7 a plurality of radially extending equidistantly spaced slots, indicated by the nu-

merals 5, are cut in the disc, extending to within a short distance of the bore 2, and in these slots are slidably mounted for inward and outward movement pawls 6, 7, 8, 9, 10 and 11 respectively, the outer ends of which are ratchet-tooth shaped and project normally a designed amount beyond the peripheral edge of the disc. Two holes, 12 and 13, are provided in the lower end of each 60 pawl and in the holes are disposed springs, 14 and 15 respectively, the lower ends of which springs rest on the bottom of their respective slots, as shown in Figs. 3 and 4, from which it will be seen that the pawls are 65 resiliently supported and spring-pressed within the slots, and in order to prevent side play of the pawls, annular plate rings 16 and 17 are secured by suitable screws 18 to the disc on each side of it, between which 70 plates the pawls are movable.

19 and 20 indicate the opposite side plates of a cover, formed as shown in Fig. 4 and indicated generally by the numeral 21, completely enclosing the disc and the pawls, 75 which cover has concentric side bosses 22 and 23 through which extend freely the bosses 3 and 4 of the disc, so that the cover 21 is thus rotatably mounted on the disc. The two side plates of the cover are flanged 80 inwardly as shown and are bolted together by bolts 24 in order to be readily assembled and disassembled, and rigidly secured to the inner periphery of the cover plate 20 is a ring 25 the inner periphery of which ring is 85 provided with a plurality of ratchet teeth 26, these teeth being spaced equidistantly around the ring and of a designed pitch, from which it will be seen that the cover is provided with an internal ratchet-toothed 90 gear and with this internal gear the pawls 6, 7, 8, 9, 10 and 11 co-operate, one pawl only, however, being engaged at a time, as shown 95 in Fig. 3.

The cover 21 is formed with a pair of 100 apertured lugs 27 and 28, to one of which, according as to whether the ratchet is for the upper spur roll or the lower one, is connected the end of a lever 29 the opposite 105 end of which is connected to the bell crank 30 which is operated by the set works of the machine, indicated generally by the numeral 31, and the construction and operation of which is well known to those skilled 110 in the art.

The bore of each boss 22 and 23 is circumferentially grooved intermediate its

length, as at 32 and 33, in each of which grooves there may be placed if desired a ring of wick to prevent oil leakage from the cover and render it dust proof.

5 The operation of ratchet devices is generally well-known and require no extended description beyond stating that rocking of the bell crank 30 by the set works mechanism 31 partially rotates the cover 21 and 10 consequently the internal gear 26 and as there is normally one of the pawls mentioned in engagement with the gear the disc 1, on one stroke of the cover, is also partially rotated, thus partially rotating the spur roll 15 shaft 34, since the disc 1 is secured to the shaft. On the return stroke of the cover, of course, no movement of the disc takes place, as the pawls are depressed against their respective springs and merely ride over the 20 gear until the end of the stroke when one of the pawls then drops into engagement with a tooth, being pressed outwardly by its springs 14 and 15.

It will be noted, however, that as opposed 25 to other ratchets in common use in which there is always present a considerable amount of lost motion and backlash, resulting in irregularities in the spur roll feed and consequently irregularity in the cutting of 30 the shingles, this defect is practically eliminated in the ratchet described in the foregoing since the multiplicity of pawls renders it unnecessary for the cover to move through a distance fractionally greater than the pitch 35 of the teeth before driving engagement is effected between the pawl and the gear, as is necessary in one pawl ratchets in which if the pawl does not engage the tooth on account of undue slackness or other reasons 40 that particular stroke is lost and the resultant lost motion renders the ratchet very inefficient; in this present case, when six pawls are used, at any point of the cover movement fractionally greater than one-sixth of the pitch one of the pawls must necessarily engage the gear so that the possibility 45 of excessive lost motion is entirely eliminated and thus great regularity of the spur roll feed is obtained and uniformity of the 50 shingles positively assured. It should be pointed out that any practical number of pawls may be employed and by increasing the number the adjustment may be made as fine as may be desired and lost motion or 55 slackness reduced to the absolute minimum.

The construction illustrated enables a ratchet to be provided which is not heavy

or cumbersome but which on the other hand is extremely light when the purpose for which it is or may be employed is considered 60 and this advantage is attained without sacrificing strength, durability, or efficiency, from which it will be seen that I have devised a ratchet which is of great utility and advantage wherever it may be used and particularly in co-operation with the spur rolls of shingle machines.

What I claim as my invention is:—

1. A ratchet comprising an annular plate disc having a central bore extending through 70 concentric side bosses and a plurality of radially extending slots in each of which is slidably mounted a pawl, each said pawl projecting beyond the disc periphery, springs in 75 each slot on which its respective pawl is seated, annular plate rings secured to the disc on its opposite sides forming side walls for the slots, and a cover in which said disc is enclosed provided with an internal ratchet-toothed gear with which said pawls one at a 80 time are engageable, said cover having concentric side bosses in which the disc bosses are freely mounted.

2. A ratchet comprising a disc provided 85 with spring pressed pawls projecting radially from it and having annular plate rings secured to it on opposite sides forming side walls between which said pawls operate, and a cover in which said disc is enclosed formed in two portions detachably connected together one of which portions is provided with an internal ratchet-toothed gear with which said pawls one at a time are engageable.

3. A ratchet comprising an annular plate 95 disc having a central bore extending through concentric side bosses and a plurality of radially extending slots in each of which is slidably mounted a pawl, each said pawl projecting beyond the disc periphery, springs in 100 each slot on which its respective pawl is seated, annular plate rings secured to the disc on its opposite sides forming side walls for the slots, and a cover in which said disc is enclosed formed in two portions detachably connected together one of which is provided with an internal ratchet-toothed gear 105 with which said pawls one at a time are engageable, said cover having concentric side bosses in which the disc bosses are freely mounted.

Dated at Vancouver, B. C., this 10th day of September, 1923.

HARRY BARRETT WEBB.
